INVENTOR.

Harry S. Daubert.

BY William J. Jackson
ATTORNEY.

UNITED STATES PATENT OFFICE.

HARRY S. DAUBERT, OF AMARILLO, TEXAS.

RAILWAY EQUIPMENT.

Application filed March 20, 1923. Serial No. 626,265.

To all whom it may concern:

Be it known that I, HARRY S. DAUBERT, a citizen of the United States, residing at the city of Amarillo, county of Potter, and State of Texas, have invented a certain new and useful Improved Railway Equipment, of which the following is a specification.

This invention, generally stated, has relation to railway equipment and has more especial relation to an improved rail and rail-joint.

As at present constructed, considerable difficulty is experienced with rail-joints becoming chipped, battered, fractured or mutilated. Specifically stated this trouble occurs at the rail ends upon that portion of the rail usually termed the rail ball. This results in the running surface or rail ball top adjacent a joint becoming impaired the disadvantage of which is readily apparent. The direct cause of the trouble is that a moving train operates to impart vertical, frictional contact of the rail ends with respect to one another first causing the rail tops to chip and subsequently the rail ends to become battered. Obviously climatic conditions alter the degree of frictional contact since under rail expansion the degree of frictional contact is more marked than it is under rail contraction. According to modern railway practice it is customary to build up such chipped, battered, fractured or mutilated rail parts by means of acetylene welding. This requires the employment of skilled labor and is therefore an expensive procedure.

The leading object of the present invention is to overcome the above described disadvantageous features and provide a rail construction in which the chipping, battering, fracturing or mutilation of rail joints is eliminated thus avoiding the necessity for employing acetylene welding in keeping the track in repair. A further object resides in the provision of means for attaining the results sought by said leading object. A further object is to provide a rail construction in which rails may be manufactured at a cost not in excess of standard rail production and which may be used as part of standard railway equipment without employing special fish-plates, splices or the like. Other and further objects not at this time more specifically referred to will appear herein-after.

The invention consists of the improve-

ments hereinafter described and finally claimed.

The nature, characteristic features and scope of the invention will be more fully understood from the following description taken in connection with the accompanying drawings, forming part hereof, and in which:

Fig. 1, is a view in side elevation of a rail embodying features of the invention.

Fig. 2, is an end view thereof drawn to an enlarged scale, and

Fig. 3, is a fragmentary view, in side elevation, illustrating a rail-joint as effected in accordance with the present invention.

For the purpose of illustrating my invention I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

According to the present invention preferably one end of a rail 10 is cut away as at 11. Obviously both ends may be so cut away if desired. In practice this cut is effected upon that part of the rail known as the rail ball which is designated 12. Considered longitudinally of the rail the cut-away portion is of a depth of three-eighths ($\frac{3}{8}$) of an inch and considered vertically of the rail said cut-away portion is equal to the height of the rail ball and extends laterally across the entire face of the rail ball. The rail web 13 and rail base 14 remain intact and are of conventional formation. While obviously, the cut-away portions 11 may be made upon tracks now installed; or before the rails are installed; in practice it is desirable to have the same accomplished at the rail mills at the time of rail manufacture. The cutting of rail ends adds little or no expense to rail manufacture. In practice a rail having a cut-away portion is arranged so that said portion is positioned adjacent an un-cut end of a companion rail, see Fig. 3, with the webs and bases of the respective rails abutting as usual. Thus there is left between the rail balls a comparatively small opening or space which is never closed and the opposed

2
ends of said rail balls are thus never in frictional contact. Consequently vertical movement of the rails, due to a train moving thereover, cannot cause chipping of the 5 rail top surface with consequent battered ends as now prevalent. In consequence thereof building-up of chipped and battered rail parts by acetylene welding is eliminated. In this connection it may be 10 stated that the invention is applicable to different sizes and types of traction rails and that special fish-plates, splices and the like are unnecessary since conventional rail webs and bases are used and consequently 15 standard fish-plates may be employed.

It will now be apparent that I have devised a novel and useful construction which embodies the features of advantage enumerated as desirable in the statement of the invention and the above description and while I have in the present instance shown and described the preferred embodiment thereof which has been found in practice to give satisfactory and reliable results, it is to be 20 understood that the same is susceptible of modification in various particulars without departing from the spirit or scope of the invention or sacrificing any of its advantages.

25 90 What I claim is:

1. A traction rail comprising a conven-

tional base, web and ball portion, which ball portion is slightly cut away at a rail end so that when positioned adjacent a companion rail ball there is present a permanently open space between the rail balls so that frictional contact thereof is eliminated in vertical movement of a rail due to traction thereover whereby chipping of the rail top surface with a consequent battered end 40 is prevented.

2. In combination, traction rails each comprising a conventional base, web and traction portion, which traction portion is slightly cut-away at a rail end to provide 45 clearance leaving the base and web intact to effect the usual rail-joint and conventional means for securing said rails together, substantially as and for the purposes set forth.

3. In combination, traction rails each comprising a conventional base, web and ball portion, which ball portion is slightly cut away at a rail end to provide clearance, leaving the base and web intact to effect the usual rail-joint, a rail having an un-cut ball portion being opposed to the cut end of a rail and a conventional fish-plate for securing said rails together.

In testimony whereof, I have hereunto 50 signed my name.

HARRY S. DAUBERT.
